UNITED STATES PATENT OFFICE.

WILLIAM STANLEY, JR., OF GREAT BARRINGTON, MASSACHUSETTS, ASSIGNOR
TO GEORGE WESTINGHOUSE, JR., OF PITTSBURG, PENNSYLVANIA.

DYNAMO-ELECTRIC MACHINE.

SPECIFICATION forming part of Letters Patent No. 372,945, dated November 8, 1887.

Application filed February 16, 1887. Serial No. 227,766. (No model.)

To all whom it may concern:

Be it known that I, WILLIAM STANLEY, Jr., a citizen of the United States, residing in Great Barrington, in the county of Berkshire and State of Massachusetts, have invented certain new and useful Improvements in Dynamo-Electric Machines, of which the following is a specification.

The invention relates to the construction of the armatures employed in electric generators, and its object is to provide an armature-core which shall be free from Foucault currents and consequent heating, and which may be easily and cheaply manufactured.

15 The invention consists in forming an armature-core in substantially the following manner: Upon a suitable shaft there is mounted a cast-iron frame consisting of two end plates or disks connected by bars of approximately 20 the length of the armature. One of the end plates is constructed with a flange extending outward to the periphery of the armature. These plates are of soft iron having a diameter equal to that of the flange, and they each 25 have a central opening. They are placed upon the frame side by side, and bound firmly in 30 position by another plate of cast-iron which is secured upon the shaft. The soft-iron plates are preferably insulated or magnetically separated from each other by sheets of insulating material—as, for instance, paper.

The invention is illustrated in the accompanying drawings, in which Figure 1 is a longitudinal section of the core, and Fig. 2 is a cross-section.

35 Referring to the figures, A represents the shaft of the armature, and B the cast-iron frame. This consists of two end plates, a' a'' , united by rods b b , four of which are shown in the 40 drawings. The plate a'' is constructed with a flange, a^3 , which extends outward to the periphery of the completed armature. Upon this frame there are placed plates c c , of soft iron, having openings of such size as to fit 45 snugly upon the frame. The plates are preferably separated from each other by thin sheets D D , of paper or other suitable non-magnetic material. The plates are bound in

position by the plate D, which is preferably screwed upon the shaft A and rests against 50 the end of the series of plates and the end plate, a , of the frame. A nut, D', may be applied to the shaft independently of the plate D, or the two parts may be constructed together. The frame itself is keyed to the shaft, 55 as shown at e , or fastened in any suitable manner.

The plates c c may, if desired, be made with lugs or projections upon their circumference, and it is not desired to limit the invention to 60 any special outline of plates.

I claim as my invention—

1. The combination, with the shaft of the armature of an electric machine, of an armature-core consisting of a frame of cast-iron independent of but carried upon said shaft, plates of soft iron upon the frame, sheets of non-conducting material between said plates, and a cast-iron end piece binding the plates in position. 70

2. In an armature-core, the combination of the frame consisting of end plates, rods or bars uniting the same, one of which plates is widened, plates of soft iron mounted upon said frame, and a binding-plate applied to the 75 end of the frame opposite said widened plate.

3. In an armature-core, the combination of a frame of cast-iron, consisting of the end plates, a' a'' , the connecting-bars b b , plates of soft iron placed upon the frame, the binding-plate D, and the shaft upon which the binding-plate is screwed. 80

4. The combination, with the armature shaft of an electric machine, of an armature-core consisting of a frame independent of the shaft, 85 but carried thereby, and consisting of end plates and longitudinal bars uniting the same, leaving an annular open space about the shaft, and insulated soft-iron plates upon the frame.

In testimony whereof I have hereunto subscribed my name this 8th day of January, A.D. 1887.

WILLIAM STANLEY, JR.
